WELL TOOL SWIVEL DEVICE

Reuben C. Baker, Coalinga, Calif., assignor to
 Baker Oil Tools, Inc., Vernon, Calif., a corpora-
 tion of California

Application July 1, 1946, Serial No. 680,665

12 Claims. (Cl. 166—12)

1

This invention relates to well tools especially useful in the performance of cementing, acidizing, washing, testing, anchoring and similar functions in oil and gas wells.

Certain well tools are operable by moving their parts with respect to one another through manipulation of an attached tubing string. The relative movement may result from holding one of the tool parts relatively stationary through casing or formation engaging instrumentalities, or by otherwise resisting its movement. Some such devices are in engagement with the wall of the casing or formation and tend to resist rotation of the well tool when rotation of the attached tubing string, without corresponding revolution of the devices, might be desirable. An example of the desirability of not rotating the casing or formation engaging instrumentalities is in removing the well tool from the well bore by unscrewing the tubing or drill pipe joints very readily through rotation, by the rotary table at the top of the hole, of the entire tubular string remaining in the well bore. Where such rotation has been attempted in the past, the casing or formation wall engaging means has also been rotated, with potential damage to it and to other parts of the well tool.

Accordingly, it is an object of the present invention to permit the tubing string to be rotated without corresponding rotation of the well tool elements engaging the casing or formation wall.

Another object of the invention is to provide a well apparatus in which the tubing string to which the well apparatus is attached may be rotated without rotating the apparatus itself.

A further object of the invention is to provide for the rotation of the tubing string without corresponding rotation of a well tool attached to the tubing string, in which the tool and tubing string may be positively coupled together to allow at least part of the well tool to rotate in unison with the tubing string.

Still another object of the invention is to provide a well tool embodying a locking device controlled by movement of a tubing string, to which the well tool is attached, with respect to a casing engaging drag service constituting part of the well tool, the tubing string being movable to operate the locking device in its normal manner and yet rotatable through a large number of revolutions without corresponding rotation of the drag device.

Another object of the invention is to provide a well tool for anchoring to a casing, which can be forcibly retracted from engagement with the casing through rotation of a tubular string to

2

which the tool is attached, without rotating a casing engaging drag device forming part of the tool.

This invention has other objects which will become apparent from a consideration of the embodiments shown in the drawings accompanying and forming part of the present specification. These forms will now be described in detail to illustrate the general principles of the invention, but it is to be understood that such detailed description is not to be taken in a limited sense, since the scope of the invention is best defined by the claims appended hereto.

Referring to the drawings:

15 Figure 1 is a longitudinal section, partly in elevation, of one form of the invention positioned within a well casing;

Figure 2 is a longitudinal section on an enlarged scale of the swivel device shown in Figure 1;

Figure 3 is a cross-section taken along the line 3—3 in Figure 2;

Figure 4 is a cross-section taken along the line 4—4 in Figure 2;

20 Figure 5 is a longitudinal section through another embodiment of the invention;

Figure 6 is a longitudinal section through still another form of the invention; and

25 Figure 7 is a view like Figure 6, with parts in another operative position.

The invention is illustrated in the drawings as applied to a well tool A movable through a well casing B by virtue of its attachment to a tubular string C of tubing or drill pipe. The tool disclosed is a well packer of the type described in my United States Patent 2,368,400, in which an upper body or mandrel 10 is connectable to the lower end of the tubing string, and is attached to a lower body 11 by means of a suitable left hand threaded connection 12. A packing actuator 13 is secured to the lower end of the lower body 11 and engages a packing sleeve 14 surrounding the body, whose upper end contacts a conical slip expander 15 having upwardly and inwardly tapering surfaces 16 engageable with companion surfaces 17 on a plurality of spaced circularly disposed slips 18 supported by a sleeve 19 through the medium of pins 20 and links 21.

The sleeve 19 is connected by a suitable swivel 22 to a collar or sleeve 23 forming part of a lock device, and embodying a slot 24, 25 of J or L shape in which a lock pin 26 secured to the mandrel 10 may move. The sleeve has a drag service attached to it, which, as shown in the drawings, includes a plurality of circularly spaced outwardly bowed leaf springs 27, whose lower ends are

suitably secured to the sleeve 23, as by an encircling ring 28 and screws 29, and whose upper ends are also suitably secured to an upper collar 30 slidably on the mandrel 10, as by an encircling ring 31 and screws 32.

As explained in the above patent, the packer A is movable through the well casing B with its parts locked in retracted position, as governed by the location of the lock pin 26 in the horizontal portion 24 of the lock slot. When in such position, the slips 18 and expander 15 cannot move longitudinally with respect to one another to anchor the former to the wall of the well casing. But when anchoring is desired, the tubing string C is rotated to the left or counterclockwise (looking down) to position the lock pin 26 at the lower end of the longitudinal slot portion 25. Relative rotation between the mandrel 10 (and its lock pin) and the lock sleeve 23 takes place, since the frictional force of the drag springs 27 against the wall of the casing resists or prevents corresponding rotary movement of the sleeve 23.

The moving of the tubing string C and attached mandrel 10 and lower body 11 in an upward direction then moves the packing sleeve 14 and conical expander 15 upwardly with respect to the slips 18, which are held stationary by virtue of their coupling to the friction drag device 27, the expander 15 shifting the slips 18 outwardly into anchoring engagement with the casing wall, which prevents further upward movement of the expander, after which a continuation of the upward movement of the tubing string, mandrel and body foreshortens the packing sleeve 14 between the expander 15 and packing actuator 13 and expands it radially outward into leakproof sealing engagement with the wall of the casing.

The desired operation in the well bore may now take place, and when completed, the tool may be retrieved from the well casing by lowering the tubing string C and connected mandrel 10 and lower body 11, which shifts the lock pin 26 downwardly of the sleeve 23 (held stationary by the drag springs), and then turning the tubing string to the right to relocate the lock pin in the horizontal slot portion 24 of the locking device, in which position the packing 14 and slips 18 are again held in retracted position. The tool may now be elevated in the well casing to the top of the well bore.

In elevating the tool, rotation of the tubing string in the well casing may be desirable to unscrew rapidly and easily the sections or stands of tubing or drill pipe positioned above the rotary table at the top of the well bore. Such rotation ordinarily produces revolution of the friction drag device 27, since the rotary motion of the tubing is transmitted to the drag device through the mandrel pin 26 and lock slot sleeve 23. If such rotation of the entire tubing string to produce rapid unthreading of the pipe sections removed from the well bore is attempted, the friction drag device 27 and other parts of the well tool might be damaged in being dragged around the casing wall. As a consequence, disconnection of the tubing sections above the rotary table is usually effected by keeping the tubing string in the well bore stationary and rotating the tubing sections above the table to the left, which consumes much more rig time and is more tedious than the desirable manner of rotating the tubing string in the well casing by means of the power driven rotary table.

The present invention provides a device which

permits the tubular string in the well casing to be rotated without rotating the drag device, and without rotating the well packer itself, unless such rotation is purposely desired. The invention also includes the ability to unscrew the left hand threaded connection 12 whenever the slips 18 and packing 14 are to be forcibly retracted.

Specifically, as shown in the embodiment of Figures 1 to 4, a swivel 33 is incorporated between the tubular string C and the mandrel 10, which is capable of transmitting sufficient rotary force between the tubing string and mandrel to operate the lock device 23, 26, but which is incapable of transmitting sufficient rotary force to produce rotation of the drag device 27 around the casing wall.

The friction swivel, which may be considered as part of the tubing string or of the well tool, includes a collar 34 threaded to an upper tubing section 35 and to a lower inner tubular coupling member 36 received within an outer coupling member 37 threaded on a sub 38, which, in turn, is threaded on the tool mandrel 10. The inner tubular coupling member 33 has a lower enlarged head 39 carrying side seals 40 engaging the wall of the outer coupling member or cylinder 37 to prevent leakage of fluid therebetween. Upward pulls or strains between the inner and outer coupling members are transmitted from the head 39 through a suitable thrust bearing washer 41 onto a shoulder 42 in the outer coupling member 37.

The outer coupling member or cylinder is provided with an inner, upwardly diverging, tapered surface 43, in which is received a plurality of wedge-shaped friction segments 44 having external tapered surfaces 45 engageable with the outer member tapered surfaces 43, and with the inner cylindrical surfaces 46 engageable with the external cylindrical surface 47 of the inner coupling member 36. Rotation of the segments 44 with respect to the cylinder 37 is prevented by one or more pins 48 in the cylinder projecting inwardly between adjacent coupling segments.

The segments are urged downwardly into frictional engagement with the inner coupling member 36 by a helical spring 49, whose lower end bears against a thrust bearing washer 50 resting on the upper ends of the segments, and whose upper end engages an adjusting nut 51 threaded on the inner coupling member, which can be rotated to provide the required compressive force in the spring urging the segments 44 down along the cylinder tapered surface 43 and into frictional engagement with the exterior 47 of the inner coupling member 36. A suitable lock nut 52 may be threaded on the inner coupling member against the adjusting nut 51 to hold the latter in the position to which it has been moved in compressing the spring.

Rotation of the tubular string C correspondingly rotates the inner coupling member 36, and, through the frictional engagement between the latter and the friction segments 44, rotates the outer coupling member 37 and the mandrel 10 secured to it. The spring 49 is adjusted to provide sufficient frictional drive between the inner and outer coupling members 36, 37 as to permit rotary movement of the lock pin 26 in and out of the horizontal locking portion 24 of the slot, but such friction force is less than the friction of the drag springs 27 against the casing wall.

With the friction swivel device 33 included between the tool mandrel 10 and tubing section 35,

the well packer is operated in the same manner as if the friction swivel device were not present; that is, the tubing string C is rotated to the left to position the lock pin 26 in the longitudinal portion 25 of the sleeve slot and the tubing string elevated to anchor the slips 18 and expand the packing 14 against the casing B. The required rotary movement is transmitted through the friction clutch 36, 44, 37, and the necessary upward movement is transmitted through the head 39 on the inner coupling member to the shoulder 42 on the outer coupling member 37. Conversely, the lowering movement of the tubing string C will be transmitted to the mandrel 10, to realign the lock pin 26 and the horizontal portion 24 of the slot, through the adjustable spring 49 and friction segments 44, or through abutting of the inner coupling member head 39 with the upper end of the sub 33. Thereafter, rotation of the tubing string C to the right effects a friction drive of the tubular mandrel 10 to the right to position the lock pin in the horizontal lock portion 24 of the slot and locks the slips 18 and packing 14 in retracted position free from engagement with the casing B.

With the parts in this locked position, the tool may be rapidly removed from the well casing. After the tubing string is elevated in the well bore to place the permissible length of tubing above the rotary table, the tubing may be coupled to the rotary table and the tubing stand thereabove held stationary. The rotary table may now be rotated by the prime mover to unscrew the coupling or threaded joint immediately above the table, all of the tubing in the casing being correspondingly rotated to the right without rotating the well tool A, the latter being held stationary by the casing engaging friction drag springs 27 and the slipping of the inner coupling member 36 with respect to the friction clutch segments 44. As aforementioned, the friction between the inner coupling member 36 and friction segments 44 is less than the frictional force between the drag springs 27 and casing wall, which allows the inner coupling member to slip with respect to the coupling segments and outer coupling member 37, and the tool parts connected to the latter. As more and more stands of pipe are raised above the rotary table of the well bore in elevating the well tool from the casing, they may be disconnected in the same manner through rotation of the rotary table, which will not rotate the well tool, and consequently, cannot damage the tool or disrupt or twist the drag springs 27.

In the tool shown in the drawings, and as specifically described in the patent above referred to, it may sometimes be necessary to unscrew the mandrel 10 from the lower body 11 in order to forcibly retract the slips 18 from anchoring engagement in the casing B. Unscrewing of the left hand threads 12 on the mandrel from the lower body elevates a flange 53 on the mandrel 10 into engagement with the slip ring 19 and produces forcible retraction of the slips 18 from the casing B.

The present invention provides means for effecting unscrewing of the mandrel 10 in an upward direction from the body 11. Specifically, a clutch is provided at the lower end of the inner coupling member 36 adapted for downward movement into positive driving engagement with the sub 38 attached to the mandrel 10. Such positive driving engagement is accomplished by the mating of teeth or dogs 54 on the sub in companion recesses 55 in the end of the inner cou-

pling member head 36. Following such downward movement, rotation of the tubing string C effects positive rotation of the mandrel 10, to screw the latter upwardly of the body 11 and effect forcible retraction of the slips 18 from the casing. Such rotation occurs without corresponding rotation of the slips 18 by virtue of the swivel connection 22 between the lock sleeve 23 and slip ring 19.

After the slips 18 have been forcibly retracted in the manner described, upward movement of the tubing string C elevates the inner coupling member 36 out of positive clutching engagement with the sub 38, and allows rotation of the tubing string and inner coupling member without corresponding rotation of the outer coupling member 37, sub 38, mandrel 10, friction drag device 27 and other parts of the well tool.

In the form of invention illustrated in Figure 20 5, the well tool may be rotated without rotating the friction drag device, and relative rotation between the mandrel 10 and lower body 11 may be effected without the necessity of employing a releasable coupling, such as the positive dog clutch 25 54, 55 in the above described form of the invention. The tubing string C is connected directly to the mandrel 10, and a friction swivel connection is provided between the lock sleeve 23 and the friction drag device 27.

As shown in the drawings, the swivel connection includes a clutch collar or ring 56, to which the drag springs 27 are attached, rotatable on the lock sleeve 23, but having a rotatable friction drive therewith by virtue of the engagement 30 of a clutch disc 57 with the lower end of the collar 56 and a sleeve shoulder 58, and engagement of a second clutch disc 59 with the upper surface of the collar 56 and a ring 60 having a slidable spline connection with the sleeve through 35 one or more pins 61 secured to the sleeve and loosely fitting in one or more holes 62 in the ring. The clutch discs 57, 59 are engaged frictionally with the clutch collar 56, sleeve shoulder 58 and ring 60 by a helical spring 63 encircling the sleeve 23 with its lower end engaging the ring 60 and its upper end an adjusting nut 64 threaded on the upper end of the sleeve to determine the compressive force of the spring.

The force exerted by this spring 63 is so chosen 50 that the friction clutch prevents rotary movement between the sleeve 23 and friction drag device 27 in allowing rotation of the lock pin 26 into and from the horizontal locking portion 24 of the J slot. However, the friction clutch will slip and allow the lock sleeve 23 to rotate with respect to the drag device 27 before the drag device can be rotated around the wall of the casing B.

Thus, in the Figure 5 embodiment, the tool may 60 be operated in moving the slips 18 and packing 14 into and from engagement with the casing, with their relative movement determined by the frictional engagement of the drag device 27 against the casing and the position of the lock pin 26 in the lock slot 24, 25. Moreover, upward movement of the mandrel 10 with respect to the body 11 through rotation of the former to effect unthreading of the mandrel at the left hand threads 12 can take place in the usual manner. Such rotary movement of the mandrel 10, however, will not be transmitted to the friction drag device 27, for the reason that the friction clutch at the lower end of the drag device will slip and the upper drag collar 30 is always 70 free on the mandrel 10.

Similarly, after the parts of the tool have been retracted and the lock pin 26 positioned in the horizontal lock portion 24 of the slot, the tool may be rotated out of the hole in effecting disconnection of the stands of tubing above the rotary table, without rotating the drag device 27 around the casing B. Since the slips and packing are in retracted position their rotation with the tubing string can occur without damage.

The two forms of friction swivels have been described heretofore in conjunction with a well tool having casing engaging slips and/or an expandable packing. The invention is not limited to the particular type of tool described in Figures 1 to 5, but may be used in other well tool devices. For example, the tool illustrated in Figures 6 and 7 employs a drag device 65 connected to an operating rod 66 extending into a valve housing 67 for controlling the ability of a ball valve member 68 to move downwardly into engagement with its seat 69. The valve housing 67 is connected to a string of tubing C running to the top of the well bore.

The valve operating rod 66 carries a pin 70 movable in an inverted J or L slot 71, 72. When the tubing string C has been lowered with respect to the operating rod 66, which tends to remain stationary because of the engagement of its drag springs 65 with the casing wall, the upper end of the rod 66 engages the ball valve 68 to elevate it from its seat 69. The turning of the tubular string C to the right then positions the lock pin 70 in the horizontal portion 71 of the slot and maintains the rod upwardly, holding the ball valve from the seat and permitting fluid to be pumped downwardly through the tubing string C, around the elevated ball valve member 68, through the seat 69, and out of the valve housing ports 73 below the seat to the exterior of the tubing string. With the pin 70 in the horizontal slot portion 71, or in ball elevating position, the tubing string C may be lowered or elevated in the casing without engagement of the ball 68 with its seat 69, which would close the tubing string to downward flow of fluid therethrough and out through the ports 73.

Conversely, rotation of the tubing string to the left shifts the pin 70 into the upper end of the longitudinal slot portion 72 and permits elevation of the tubing string to remove the operating rod 66 from engagement with the valve ball member 68, allowing the latter to reengage its seat 69.

In the event it is desired to effect disconnection of the tubing sections elevated above the rotary table from the tubing remaining in the well casing by the rotary table, without rotating the drag springs 65 around and along the wall of the casing B, a frictional swivel device such as disclosed in Figures 1 to 4 may be incorporated in the tubing string C above the valve housing 67; or a friction swivel device may be included between a lower drag spring collar 74 and the operating rod 66.

The arrangement in Figures 6 and 7 includes the outer drag collar 74 mounted around an inner drag sleeve 75 threaded on the valve operating rod 66, and locked thereon by a suitable nut 76. A friction clutch disc 77 is located between the drag collar 74 and a lower sleeve shoulder 78, with a helical spring 79 surrounding the sleeve and compressed between the collar or ring 74 and a thrust bearing washer 80 abutting an adjusting nut 81 threaded on the upper end of the sleeve 75. The spring 79 urges the collar 74, friction disc 75

77 and sleeve shoulder 78 into frictional clutch driving relation with respect to one another.

The operation of the apparatus shown in Figures 6 and 7 is substantially the same as in the slip well packer shown in Figure 5. The frictional force exerted between the clutch disc 77 and its engaging members 74, 78 is less than the frictional force of the drag springs 65 against the wall of the well casing B. This frictional clutch force, however, is sufficient to hold the valve operating rod 66 relatively stationary to permit movement of the lock pin 70 within the lock slot 71, 72 in controlling operation of the ball valve 68 with respect to its seat 69. If the tubing string C is rotated, the entire apparatus, with the exception of the drag springs 65, its connected upper and lower collars 74, 74a and coil spring 79, is rotated, preventing the need for forcible sliding of the drag springs 65 around the casing wall. In this manner, the well tool may be quickly removed from the well casing through rotation of the tubing string by the rotary table at the top of the hole.

While I have described several embodiments of my invention, what I claim and desire to secure by Letters Patent is:

1. Well apparatus adapted to be lowered in a well conduit or the like on a tubular string, including normally retracted slips, expander means for moving said slips into engagement with said well conduit, releasable lock means for preventing substantial relative longitudinal movement between said slips and expander means, tubular means operatively connected to said expander means and connectable to said tubular string, a drag device frictionally engageable with said well conduit and rotatably connected to said slips, and friction clutch means for coupling said drag device to said lock means, said friction clutch means having a load transmitting capacity sufficient to effect operation of said lock means, but insufficient to overcome the normal resistance to movement offered by said drag device when engaging said well conduit.

2. Well apparatus adapted to be lowered in a well conduit or the like on a tubular string, including a first part, a second part cooperable with said first part, a releasable lock for locking said parts together to prevent substantial relative movement between said parts, tubular means operatively connected to said first part and connectable to said tubular string, drag means operatively connected to said second part and frictionally engageable with said well conduit to resist movement of said second part therewithin, friction clutch means for coupling said lock to one of said means, said friction clutch means having a load transmitting capacity sufficient to effect operation of said lock, but insufficient to overcome the normal frictional resistance to movement offered by said drag means when engaging said well conduit, and means for adjusting said friction clutch means to predetermine the maximum torque transmittable therethrough without slippage.

3. Well apparatus adapted to be lowered in a well conduit or the like on a tubular string, including a first part, a second part cooperable with said first part, a releasable lock for locking said parts together to prevent substantial relative movement between said parts, tubular means operatively connected to said first part and connectable to said tubular string, drag means operatively connected to said second part and frictionally engageable with said well con-

duit to resist movement of said second part therewithin, and friction clutch means for coupling said lock to one of said means, said friction clutch means having a load transmitting capacity sufficient to effect operation of said lock, but insufficient to overcome the normal frictional resistance to movement offered by said drag means when engaging said well conduit.

4. Well apparatus adapted to be lowered in a well conduit or the like on a tubular string, including a first part, a second part cooperable with said first part, releasable lock means for locking said parts together to prevent substantial relative movement between said parts, tubular means rotatably connected to said first part and connectible to said tubular string, a device operatively connected to said second part and frictionally engageable with said well conduit to resist movement of said second part therewithin, friction clutch means connecting said tubular means to said first part for transmitting the torque of said tubular means to said first part, said friction clutch means having a load transmitting capacity sufficient to effect operation of said lock means, but insufficient to overcome the normal frictional resistance to movement offered by said device when engaging said well conduit.

5. Well apparatus adapted to be lowered in a well conduit or the like on a tubular string, including a first part, a second part cooperable with said first part, releasable lock means for locking said parts together to prevent substantial relative movement between said parts, tubular means rotatably connected to said first part and connectible to said tubular string, a device frictionally engageable with said well conduit and rotatably connected to said second part to resist movement of said second part therewithin, friction clutch means between said device and second part for transmitting the torque imposed on said second part to said device, said friction clutch means having a load transmitting capacity sufficient to cause said device to resist rotation of said lock means in order to effect operation of said lock means, but insufficient to overcome the normal frictional resistance to movement offered by said device when engaging said well conduit.

6. Well apparatus adapted to be lowered in a well conduit or the like on a tubular string, including a first part, a second part cooperable with said first part, releasable lock means for locking said parts together to prevent substantial relative movement between said parts, tubular means rotatably connected to said first part and connectible to said tubular string, a device operably connected to said second part and frictionally engageable with said well conduit to resist movement of said second part therewithin, friction clutch means connecting said tubular means to said first part for transmitting the torque of said tubular means to said first part, said friction clutch means having a load transmitting capacity sufficient to effect operation of said lock means, but insufficient to overcome the normal frictional resistance to movement offered by said device when frictionally engaging said well conduit, a positive drive clutch element on said tubular means, and a positive drive clutch element on said first part engaged by said clutch element on said tubular means upon downward movement of said tubular means relative to said first part.

7. Well apparatus adapted to be lowered in a

well conduit or the like on a tubular string, including a first part, a second part cooperable with said first part, releasable lock means for locking said parts together to prevent substantial relative movement between said parts, tubular means rotatably connected to said first part and connectible to said tubular string, a device operably connected to said second part and frictionally engageable with said well conduit to resist movement of said second part therewithin, friction clutch means connecting said tubular means to said first part for transmitting the torque of said tubular means to said first part, said friction clutch means having a load transmitting capacity sufficient to effect operation of said lock means, but insufficient to overcome the normal frictional resistance to movement offered by said device when engaging said well conduit, a positive drive clutch element on said tubular means, a positive drive clutch element on said first part engaged by said clutch element on said tubular means upon downward movement of said tubular means relative to said first part, and spring means bearing upon said friction clutch means and tubular means and tending to elevate said tubular means with respect to said first part to disengage said clutch element on said tubular means from said clutch element on said first part.

8. Well apparatus adapted to be lowered in a well conduit or the like on a tubular string, including normally retracted slips, expander means for moving said slips into engagement with said well conduit, a releasable lock for preventing substantial relative longitudinal movement between said slips and expander means, tubular means operatively connected to said expander means and connectible to said tubular string, a drag means frictionally engageable with said well conduit and operatively connected to said slips, and slippable friction clutch means for coupling said lock to one of said means, said friction clutch means having a load transmitting capacity sufficient to effect operation of said lock, but insufficient to overcome the normal frictional resistance to movement offered by said drag means when engaging said well conduit.

9. Well apparatus adapted to be lowered in a well conduit or the like on a tubular string, including normally retracted slips, expander means for moving said slips into engagement with said well conduit, tubular means connectible to said tubular string, a drag device frictionally engageable with said well conduit and operatively connected to said slips, releasable lock means for locking said expander means to said drag device to prevent substantial relative longitudinal movement between said slips and expander means, and slippable friction clutch means connecting said tubular means to said expander means for transmitting the torque of said tubular means to said expander means, said friction clutch means having a load transmitting capacity sufficient to effect operation of said lock means, but insufficient to overcome the normal frictional resistance to movement offered by said drag device when frictionally engaging said well conduit.

10. Well apparatus adapted to be lowered in a well conduit or the like on a tubular string, including normally retracted slips, expander means for moving said slips into engagement with said well conduit, tubular means connectible to said tubular string and rotatably connected

to said expander means, a drag device frictionally engageable with said well conduit and operatively connected to said slips, releasable lock means for locking said expander means to said drag device to prevent substantial relative longitudinal movement between said slips and expander means, slippable friction clutch means connecting said tubular means to said expander means for transmitting the torque of said tubular means to said expander means, said friction clutch means having a load transmitting capacity sufficient to effect operation of said lock means, but insufficient to overcome the normal frictional resistance to movement offered by said drag device when frictionally engaging said well conduit, a positive drive clutch element on said tubular means, and a positive drive clutch element on said expander means engaged by said clutch element on said tubular means upon downward movement of said tubular means relative to said expander means.

11. Well apparatus adapted to be lowered in a well conduit or the like on a tubular string, including a first part, a second part cooperable with said first part, releasable lock means for locking said parts together to prevent substantial relative movement between said parts, tubular means rotatably connected to said first part and connectible to said tubular string, a device operably connected to said second part and frictionally engageable with said well conduit to resist movement of said second part therewithin, a positive drive clutch element on said tubular means, a positive drive clutch element on said first part engaged by said clutch element on said tubular means upon downward movement of said tubular means relative to said first part, and coengaging means on said tubular means and first part limiting upward movement of said tubular means with respect to said first part to a position in which said clutch ele-

ments are disengaged and said tubular means is free to rotate relative to said first part.

12. Well apparatus adapted to be lowered in a well conduit or the like on a tubular string, including normally retracted slips, expander means for moving said slips into engagement with said well conduit, tubular means connectible to said tubular string, and rotatably connected to said expander means, a drag device frictionally engageable with said well conduit and operatively connected to said slips, releasable lock means for locking said expander means to said drag device to prevent substantial relative longitudinal movement between said slips and expander means, a positive drive clutch element on said tubular means, a positive drive clutch element on said expander means engaged by said clutch element on said tubular means upon downward movement of said tubular means relative to said expander means, and coengaging means on said tubular means and expander means limiting upward movement of said tubular means with respect to said expander means to a position in which said clutch elements are disengaged and said tubular means is free to rotate relative to said expander means.
